UNITED STATES PATENT OFFICE.

JOHN W. L. HENCKEL, OF YONKERS, NEW YORK, ASSIGNOR TO DURAND & COMPANY,
OF NEWARK, NEW JERSEY.

DESIGN FOR A COMBINED PENCIL AND CIGAR-CUTTER.

48,377.

Specification for Design.

Patented Jan. 4, 1916.

Application filed October 28, 1915. Serial No. 58,505. Term of patent 7 years.

To all whom it may concern:

Be it known that I, JOHN W. L. HENCKEL, a citizen of the United States, residing at Yonkers, county of Westchester, and State of New York, have invented a new, original, and ornamental Design for Combined Pencil and Cigar-Cutters, of which the following is a specification, reference being had to the accompanying drawing, forming part thereof.

Figure 1 is a side view of a combined pencil and cigar cutter showing my new design. Fig. 2 is a bottom view, and Fig. 3 is an end view thereof.

I claim:

The ornamental design for a combined pencil and cigar cutter, as shown.

JOHN W. L. HENCKEL.
